UNITED STATES PATENT OFFICE

2,129,006

FRONT FACING OARLOCK

Albert C. Kahn, Tomahawk, Wis.

Application August 31, 1936, Serial No. 98,655

3 Claims.

(Cl. 9—25)

This invention relates to a front facing oar lock and concerns itself with a simple and novel manner of mounting a jointed oar so that its operation will propel the boat in the same direction as the operator is facing.

The invention comprises the novel structure and combination of parts hereinafter described and more particularly pointed out and defined in the appended claims.

10 In the accompanying drawing which illustrates a preferred form of this invention and in which similar reference numerals refer to similar features in the different views:

Figure 1 is a top plan view of an oar lock involving this invention and showing in dotted lines the operation of the oar.

15 Figure 2 is an enlarged fragmentary sectional view taken in a longitudinal direction through the oar and lock.

20 Figure 3 is an enlarged sectional view taken substantially upon the line III—III of Figure 1 looking in the direction of the arrows.

Figure 4 is an enlarged top plan view of the fulcrum plate.

25 In the drawing which illustrates one form of the invention, there is shown a side wall 1 of a rowboat having ears 2 projecting above the top and to which there is pivoted a fulcrum plate 3. It will be noted that the fulcrum plate has curved 30 downwardly directed flanges 4 which are pivoted to the ears 2 by a bolt 5. The ears 2 which may be formed integral with a metal plate 6 are held in spaced relation by a sleeve 7 on the bolt 5. It will be noted that the fulcrum plate 3 can 35 properly tilt on the bolt 5 as an axis for lowering and raising the oar.

The handle portion 8 of the oar is pivoted to the fulcrum plate 3 by means of a bolt 9. A shoe 10 is attached to the outer end of the handle portion 8 of the oar. This shoe 10 comprises a bottom portion 11 and side flanges 12 in which the outer end of the oar portion 8 snugly fits. The bottom 11 of the shoe 10 extends beyond the side flanges as indicated at 11a.

40 45 The blade portion 13 of the oar is slidably pivoted to the fulcrum plate 3 in spaced relation to the section 8 by means of a bolt 14 which extends through a slot 15 in the fulcrum plate. The inner end of the blade portion or section 13 of the oar is also mounted in a shoe 10a very similar to the shoe 10 on the handle section.

45 50 It will be noted that the bottom of the shoe 10a also extends beyond the side flanges as indicated at 16. The shoe extensions 11a and 16 overlap 55 and a bolt 17 extends through the overlapping

portions other thereof and through an arcuate slot 18 in the fulcrum plate 3. The arcuate slot 18 is struck from the pivot 9 as a center. A bearing sleeve 19 preferably surrounds the bolt 17 and extends into the slot. The head 17a of the bolt 5 overlaps the edges of the slot 18 whereby the shoes 10 and 10a are pivotally anchored to the fulcrum plate 3. The shoes 10 and 10a are rigidly secured to the oar sections by the aforementioned bolts 9 and 14 and also by transverse bolts 20 10 which extend through the side flanges.

During the operation of the oar, it will be observed from Figure 1, that the blade portion 13 moves in the same general direction as the handle portion 8, the handle portion 8 pivoting on the bolt 9 and the blade portion 13 pivoting on the bolt 14, which moves inwardly in the slot 15 as the bolt 17 that connects the overlapping portions of the shoes travels in the arcuate slot 18. Thus 20 the oar acts as a compound lever; the handle portion being pivotally connected to the end of the blade portion 13. The arcuate slot 18 is struck from the pivot bolt 9 as a center, the slot 15 allowing for the necessary inward movement of the blade portion 13. 25

From the foregoing, it will be appreciated that a very simple mounting for a jointed oar has been provided that allows the oar to be mounted in the factory upon the fulcrum plate which only needs 30 to be attached to the boat. Moreover the mounting is conducive to easy operation and reduces the rowing effort.

I am aware that many changes may be made and numerous details of construction may be varied through a wide range without departing 35 from the principles of this invention, and I therefore do not purpose limiting the patent granted hereon otherwise than necessitated by the prior art. 40

I claim as my invention:

1. In a device of the class described, a fulcrum plate, an oar section pivoted to said plate, a second oar section, said fulcrum plate having a straight slot, a pivot bolt extending through said second oar section and through said slot and 45 slidably pivoting said second section to said plate in spaced relation to the first section, shoes upon the adjacent ends of said sections, said shoes having parts in overlapping relation, said plate having an arcuate slot and a pivot bolt extending through said overlapping portions and through 50 said arcuate slot and causing said pivot bolt to travel in an arcuate path.

2. In a device of the class described, a fulcrum plate having a flat body portion and downwardly 55

extending side flanges adapted for receiving pivot means, said body portion having a straight slot and a transverse arcuate slot, an oar section having a pivot pin slidably extending through said straight slot, a handle section pivoted to said body portion, said oar section and handle sections having parts in overlapping relation and a pivot pin extending through said overlapping portions and through said arcuate slot.

5 3. In a device of the class described, a pivotally mounted fulcrum plate having a flat body por-

tion, a handle section, a pivot connecting said handle section and body portion, said plate having a transverse arcuate slot struck from said pivot as a center and a longitudinally extending straight slot, an oar section having a pivot bolt extending through said straight slot, the adjacent ends of said sections having overlapping parts and a pivot bolt extending through said overlapping parts and said arcuate slot.

5 10

ALBERT C. KAHN.
